CAM GRINDING MACHINE

Clarence J. Green, Worcester, Mass., assignor to
 Norton Company, Worcester, Mass., a corpora-
 tion of Massachusetts

Application July 16, 1945, Serial No. 605,339

5 Claims. (Cl. 51—101)

1

The invention relates to grinding machines, and more particularly to a machine for grinding automotive cams, oval-shaped pistons and the like.

One object of the invention is to provide a simple and thoroughly practical cam grinding apparatus for grinding cam shapes, such as automotive cams or elliptical shapes for automotive pistons and the like. Another object of the invention is to provide a grinding apparatus in which the shape of the cam or piston being ground may be varied relative to the shape of the master cam. Another object of the invention is to provide means whereby the shape of the work piece being ground may be varied so as to compensate for differences in diameter of the grinding wheel caused by wheel wear or truing. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings in which is shown one possible embodiment of the mechanical features of this invention,

Fig. 1 is a fragmentary front elevation of the improved grinding machine;

Fig. 2 is a fragmentary cross-sectional view, on an enlarged scale, taken approximately on the line 2—2 of Fig. 1;

Fig. 3 is a staggered sectional view, taken approximately on the line 3—3—3 of Fig. 2, showing the relationship of the master cam and follower roller and the supporting parts therefor;

Fig. 4 is a fragmentary sectional view, taken approximately on the line 4—4 of Fig. 3; and

Fig. 5 is a diagrammatic view, showing the arrangement of the master cam and follower roller and the adjustably mounted connecting link between the supports for the master cam and the follower roller.

A grinding machine has been illustrated in the drawings comprising a base 10 which serves as a support for a longitudinally movable work supporting table 11. The table 11 is slidably supported on a V-way 12 and a flat way 13.

The work table 11 may be moved longitudinally to position it relative to the base 10 either by a power operated mechanism such as is old and well known in the art or by means of a manually operable traverse mechanism. As illustrated in the drawings, a manually operable traverse mech-

2

anism has been illustrated comprising a manually operable rotatable traverse wheel 15 which is operatively connected to rotate a gear 16. The gear 16 is mounted on a rotatable shaft 17 which is journaled in suitable bearings (not shown) in the base 10. The shaft 17 also supports a gear 18 which meshes with a rack bar 13 depending from the under side of the table 11.

A rotatable grinding wheel 20 is supported on 10 a rotatable wheel spindle (not shown) which is mounted in suitable bearings in a wheel slide 21. The wheel slide 21 is arranged to slide transversely relative to the base 10 on a V-way 22 and a flat way 23 formed on the base 10. The grinding wheel 20 is preferably rotated by an electric motor 24 which is mounted on the wheel slide 21. The motor 24 is provided with an armature shaft 25 which supports a multi-V-groove pulley 26. The multi-V-groove pulley 26 is connected 20 by multiple V-belts 27 with a multi-V-groove pulley 28 which is mounted on the right-hand end of the wheel spindle (Fig. 1).

A suitable wheel feeding mechanism is provided for feeding the grinding wheel 20 and the wheel 25 slide 21 transversely to position the wheel 20 relative to a work piece being ground and to feed the wheel 20 into the work to grind it to the desired and predetermined size. This wheel feeding mechanism has not been illustrated in detail since 30 it is not considered to be a part of the present invention. The wheel feeding mechanism is substantially the same as that which is old and well known in the grinding art such as, for example, that shown in the prior U. S. patent to Norton, No. 762,838, dated June 14, 1904, to which reference may be had for details of disclosure not contained herein. The wheel feeding mechanism may comprise a manually operable rotatable feed wheel 29 which is provided with the 35 usual micrometer feed adjusting mechanism 30. The feed wheel 29 is operatively connected through a gear mechanism (not shown) to rotate a gear 31 which is mounted on the outer end of a rotatable feed screw 32. The feed screw 32 is arranged to mesh with a half nut 33 depending from the under side of the wheel slide 21.

The work supporting table 11 serves as a support for a work rotating and driving mechanism comprising a rock bar 35 which is mounted to rock upon trunnion studs 36 and 37 which are journaled in brackets 38 and 39. The brackets 38 and 39 are fixedly mounted on the work supporting table 11.

A rotatably mounted headstock spindle 40 is 55 provided with a work holding fixture 41 to sup-

port one end of a work piece 42. The other end of the work piece 42 is supported by a footstock center 43 carried by a footstock 44. The footstock 44 is adjustably mounted on the rock bar 35.

The headstock spindle 40 is rotatably supported in a manner to be hereinafter described and is surrounded by means of a housing 45 which is fixed relative to the table 11. An electric motor 46 is provided for rotating the headstock spindle 40. The motor 46 is provided with an armature shaft 47 which supports a multi-V-groove pulley 48. The multi-V-groove pulley 48 is connected by multiple V-belts 49 with a multi-V-groove pulley 50. The multi-V-groove pulley 50 is supported on a shaft 51 journalled in a suitable bearing bracket 52 which is fixedly mounted on the table 11. The shaft 51 is connected by means of a universal joint 53 and a telescopic shaft 54 with a universal joint 55 which is operatively connected to the left-hand end of the headstock spindle 40. The headstock spindle 40 is rotatably supported in bearings 56 and 57 which are fixedly mounted on the rock bar 35.

In order to transmit a controlled rocking movement to the rock bar 35 to generate a predetermined shape on the work piece 42, a master cam 58 is supported on the headstock spindle 40. A master cam roller 60 is mounted on a rotatable shaft 61 which is in turn carried by a pivotally mounted frame 62. The frame 62 is supported by a pivot shaft 63 which is carried by a bracket 64 mounted in fixed relationship with the housing 45. The follower roller 60 is arranged operatively to engage the master cam roller 58 so that when the master cam 58 is rotated, a controlled rocking motion will be imparted to the rock bar 35 so as to rock the work piece 42 being ground toward and from the periphery of the grinding wheel to generate a predetermined shape on the work piece.

In grinding automotive cams and pistons of an oval cross-sectional area, the master cam is accurately generated to operate with a grinding wheel of a predetermined diameter. As the grinding wheel wears away due to grinding and also truing the same, the contour of the cam or piston being ground changes slightly as the wheel diameter is reduced. In production grinding, therefore, it is common practice to use a wheel of a given initial diameter and, when the wheel wears away so that its diameter is reduced a predetermined amount, to remove the wheel and replace it with a new one in order that the cam or piston contour may be maintained substantially constant. This practice means that only a small portion of a grinding wheel may be used on a given cam grinding operation, after which it must be discarded and replaced with a new wheel. It is, therefore, desirable to provide suitable adjustments whereby when the grinding wheel wears away, the rocking movement of the rock bar may be varied so as to compensate for reduction in diameter of the grinding wheel.

In order to facilitate adjusting the motion of the rock bar 35 relative to the master cam roller 60, a connecting link 70 is provided which is connected between an adjustably mounted pivot stud 72 supported by the rock bar 35 and an adjustably mounted pivot stud 71 supported by the frame 62. Adjusting screws 73 and 74 are provided for respectively adjusting the position of the pivot studs 71 and 72 relative to the frame 62 and the rock bar 35, respectively.

The pivot stud 71 is slidably supported in an elongated slot 71a (Fig. 3) to facilitate adjustment thereof. Similarly, the pivot stud 72 is supported within an elongated slot 72a (Fig. 4) to facilitate adjustment of the stud 72 relative to the rock bar 35.

A suitable mechanism is provided for maintaining the master cam 58 in operative engagement with the master cam roller 60 during a grinding operation. This mechanism may comprise a tension spring 80 which is connected at one end by means of a stud 81 with the housing 45. The other end of the spring 80 is connected by a stud 82. The stud 82 is connected by a stud 83 supported adjacent to the upper end of an arm 84 which is fixedly supported relative to the rock bar 35. The stud 81 is preferably provided with a screw threaded portion 85 which is provided with an adjusting nut 86 by means of which the tension of the spring 80 may be varied as desired.

In the diagrammatic view (Fig. 5), a master cam is shown having a long and a short axis for producing an oval or elliptical shape on a work piece such as a piston, the shape in the drawing being somewhat exaggerated diagrammatically to illustrate the operation. Due to the arrangement of the pivotal axis for the rock bar 35 and the frame 62, the pivot pin 72 at the right-hand end of the link 70 is arranged so that it may be adjusted in a path normal to the axis of the rocking of the rock bar 35. Due to the linkage arrangement, the stud 72 may be adjusted either toward or from the axis of the spindle 40 so as to vary the shape generated on the periphery of the work piece 42 in such a manner that the long axis, that is, on the line $x-y$, remains constant while the short axis at right angles thereto, namely $c-d$, may be varied by adjustment of the pivot stud 72. If it is desired to change the shape of the piston being generated so that the short axis thereof is increased, the pivot stud 72 may be lowered into position 72b, in which case the cam being ground will have a short axis, as indicated by the fragmentary broken line b . If it is desired to decrease the short axis of the piston being generated, the pivot stud 72 may be raised to position 72c, in which case the short axis of the work being ground will be decreased, as indicated by the broken line f . During each of these adjustments, due to the relationship of the pivotal supports for the rock bar 35, the frame 62 and the link connection 70, the long axis $x-y$ will remain substantially constant. The angular swinging movement of the frame 62 is preferably less than the angular swinging movement of the rock bar 35 to facilitate maintaining the master cam 58 in operative contact with the master cam roller 60. The tension of the spring 80 (Fig. 2) serves to rock the rock bar 35 so as to maintain the master cam 58 in operative engagement with the master cam roller 70. It will, therefore, be seen that by a precise adjustment of the pivot stud 72, the shape of the piston being generated may be varied so as to compensate for reduction in diameter of the grinding wheel due to wheel wear or truing so that the shape of the piston being ground may be maintained substantially constant in shape.

A similar adjustment is provided for the pivot stud 71 so that it may be adjusted in a path substantially normal to the axis of the pivot stud 63 which supports the frame 62. The pivot stud 71 may be raised into position 71c or lowered into position 71b to facilitate further adjustment to

alter the shape of the cam being produced relative to the master cam, similarly to aid in compensating for the reduction in diameter of the grinding wheel due to wheel wear or truing.

The operation of this improved cam grinding apparatus will be readily apparent from the foregoing disclosure. A cam or piston 42 to be ground is placed in position on the work supporting fixture 41 while the other end of the piston is supported by the footstock center 43. The grinding operation may then be started by starting the motors 24 and 46 and the grinding wheel 20 is fed into grinding engagement with the periphery of the piston 42 while the master cam 58 rotates in operative engagement with the master cam follower roller 60 so that a cam face or oval shape may be ground to the predetermined size and contour. As the grinding operation proceeds and the wheel 20 wears away, or is trued away during truing operations, to a point where the contour of the work piece being ground changes beyond limits, instead of replacing the grinding wheel with a new wheel the operator may adjust the position of the pivot studs 12 and/or 71 in either an upward or downward direction in a path normal to the axis of the rock bar 35 or the axis of the frame 62, as desired, to compensate for the reduction in diameter of the grinding wheel so that the cam face being produced will be changed relative to the shape of the master cam so that the contour on the finished work piece may be maintained within predetermined limits.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a cam grinding machine having a rotatable grinding wheel, a pivotally mounted rock bar, a rotatable work support on said rock bar to support a cam to be ground, a rotatable master cam on said rock bar in axial alignment with the cam to be ground, a rotatable follower roller arranged to engage the master cam, a pivotally mounted frame to support said roller, yieldable means to maintain said master cam in operative engagement with said roller, and a connecting link the ends of which are pivotally connected to said rock bar and said frame, respectively.

2. In a cam grinding apparatus having a rotatable grinding wheel, a pivotally mounted rock bar, a rotatable work support on said rock bar to support a cam to be ground, a rotatable master cam on said rock bar in axial alignment with the cam to be ground, a rotatable follower roller arranged

to engage said master cam, a pivotally mounted frame to support said roller, yieldable means to maintain said master cam in operative engagement with said roller, a connecting link, pivotal connections between the ends of said link and the rock bar and the frame respectively, and means to adjust the pivotal connections between the rock bar and the link in a direction normal to the pivotal axis of said rock bar whereby the contour of the cam being ground may be varied relative to the shape of the master cam.

3. In a cam grinding apparatus having a rotatable grinding wheel, a pivotally mounted rock bar, a rotatable work support on said rock bar to support a cam to be ground, a rotatable master cam on said rock bar in axial alignment with the cam to be ground, a rotatable follower roller arranged to engage said master cam, a pivotally mounted frame to support said roller, yieldable means to maintain said master cam in operative engagement with said roller, a connecting link, pivotal connections between the ends of said link and the rock bar and the frame respectively, and means to adjust the pivotal connections between the frame and the link in a direction normal to the pivotal axis of said rock bar whereby the contour of the cam being ground may be varied relative to the shape of the master cam.

4. In a cam grinding apparatus having a rotatable grinding wheel, a pivotally mounted rock bar, a rotatable work support on said rock bar to support a cam to be ground, a rotatable master cam on said rock bar in axial alignment with the cam to be ground, a rotatable follower roller arranged to engage said master cam, a pivotally mounted frame to support said roller, a connecting link pivotally connected at its ends at said rock bar and said frame respectively, and means to adjust the pivotal connections at both ends of said link relative to said rock bar and said frame in a direction normal to the pivotal axis of the rock bar and frame respectively to facilitate varying the shape of the cam being ground relative to the shape of the master cam, thereby compensating for reduction in wheel diameter due to wheel wear.

5. In a cam grinding apparatus having a rotatable grinding wheel, a pivotally mounted rock bar, a rotatable work support thereon to support a cam to be ground, a master cam thereon in axial alignment with said cam, the pivot of said rock bar being located below the axis of the cam and master cam, a rotatable master cam follower roller, a pivotally mounted frame for supporting said roller, the pivot of said frame being located above the axis of said master cam roller, a connecting link between said rock bar and said frame, and adjustable pivotal connections between opposite ends of said link and the rock bar and frame respectively.

CLARENCE J. GREEN.
